UNITED STATES PATENT OFFICE.

EUGEN GEGAUF, OF STECKBORN, SWITZERLAND.

HEMSTITCH SEWING MACHINE.

1,410,467.

Specification of Letters Patent. Patented Mar. 21, 1922.

Application filed January 18, 1922. Serial No. 530,157.

To all whom it may concern:

Be it known that I, EUGEN GEGAUF, a citizen of the Republic of Switzerland, residing at Steckborn, in the Canton of Thurgau, Republic of Switzerland, have invented 5 certain new and useful Improvements in Hemstitch Sewing Machines (for which I have filed an application in Switzerland, #10,370, January 17, 1921,) of which the following is a specification.

This invention relates to improvements in hem-stitch sewing machines, and more particularly, such machines comprising one or two revolving hooks or loopers located one 15 behind the other in the direction of the cloth feed and adapted to be swung from an operative or stitching position to an inoperative position, convenient for the insertion and removal of the spool of under thread. The 20 invention is designed to provide an improved construction of such machines wherein even when two loopers are employed, a feed device can be used and can be properly supported on each side of the line of the cloth 25 feed.

The accompanying drawings illustrate by way of example an embodiment of the invention consisting of an improved machine in which two rockable loopers are employed 30 located one behind the other.

In these drawings:

Fig. 1 is a plan of the improved machine, after removal of the machine top plate.

Fig. 2 is a side elevation of a looper carrier belonging thereto shown partly in section. For the sake of clearness of the drawing it is assumed that the parts that connect the looper carrier to a slide serving to rock the latter, have been placed in the plane of 40 the looper carrier; consequently Fig. 2 combines two views taken in the directions of the arrows I and II of Fig. 1.

Fig. 3 is a vertical section taken along the line A—B of Fig. 4, of a slide for rocking 45 a looper.

Fig. 4 is a plan of this slide.

Fig. 5 illustrates an apparatus for preventing the spool carrier located in the looper casing from moving with the revolving 50 looper casing.

Fig. 6 is a similar view of a modification.

Fig. 7 is a section on the line 7—7 of Fig. 6. a are the looper carriers located on opposite sides of their common driving shaft 55 w extending between them. The axis of this shaft w is at right angles to the axis of

the path of the piercer (not shown), and extends parallelly to the upper main driving shaft (not shown) of the machine. Each looper carrier is rotatably mounted on a pin 60 b screwed into a plate c fixed by means of screws d against the underside of the machine table top e. The plate c is formed with slots for the passage of the screws d so that the said plate c can be shifted along the underside of the said table top in a direction at right angles to the cloth feed, for the purpose of enabling the looper to set to different widths of hem-stitching.

On the lower end of each pin b there is 70 rotatably mounted a spur wheel f which meshes with a spur wheel g for driving the looper casing i, and is fixed to a helical wheel h. This latter wheel meshes with a helical wheel z mounted on the shaft w. Therefore, 75 as the shaft rotates the looper receives its rotary motion through the wheels z, h, f, g. On the other hand, as the looper rocks around the pin b as on an axis, the wheel g rolls over the wheel f. The two helical 80 wheels z have oppositely inclined teeth.

For rocking each looper an arm l is employed which is rotatably mounted on the looper shaft bearing k located on the looper carrier a. This arm is fixed at its free slot- 85 ted end, and carries an upwardly extending pin m which is adjustable along the slot in the arm, that is to say, is adjustable in a direction radial to the axis of the looper. The pin m is provided at its upper end with 90 an antifriction roller n working in a suitable recess in the underside of a slide o movable in the table top e. This slide is located symmetri- 95 cally to the line of the cloth feed, which line is at right angle to the axis of the path of the piercer in a plane extending at right angle to the axis of the shaft w. The axis of the pin m passes through the said line. One slide is withdrawable towards the front, whereas the other side is withdrawable to- 100 wards the rear, both beyond the longitudinal edge of the table top e (as indicated in dot-and-dash lines in Fig. 1).

Figs. 3 and 4 illustrate the slide o and the parts serving to actuate the same, drawn on 105 a larger scale. The upper surface of the slide is exactly flush with the upper surface of the machine table top e, and fills up completely the opening provided for it in the said table top, when the looper is in its operative position. For the purpose of securing the slide in this position a stem s is em-

- ployed formed with an upwardly tapering truncated conical head *q* which fits exactly into an aperture provided in the slide *o*, when the latter is in its normal position.
- 5 The stem *s* is slidably mounted in a bearing *t* which is fixed against the underside of the table top *e* by means of screws *u*. *r* is a spring located in a recess in the bearing *t*; it encircles the stem *s* between the head *q* 10 and the bearing *t*, and presses the head *q* against the slide *o*. The screws *u* have a certain amount of play in the bearing *t*, so as to allow of adjusting the said bearing relatively to the slide *o*, in order that the 15 head *q* shall fit exactly in the aperture provided for its reception in the said slide.
- When it is desired to draw out a slide *o*, for instance into the position indicated in dot-and-dash lines in the lower part of Fig.
- 20 1, for the purpose of rocking a looper; the operator presses with his finger upon the head *q* so as to depress the latter below the slide *o*, whereupon he is then immediately able to pull out the slide by means of the 25 same finger which remains in the aperture thus opened. By the pulling out of one or the other slide *o* the corresponding looper carrier *a* is caused by the intermediary of the parts *n*, *m*, *l*, *k*, to swing outwards 30 around the pin *b* as a centre. In this movement the looper which, for known reasons, lies somewhat to one side (the one looper to the left, and the other looper to the right) of the line of the cloth feed during the 35 working of the machine is thus brought on to the actual line of feed, that is to say, under the portion (opened by the pulling out of the slide) of the opening provided in the machine table top, so that the said looper is 40 thus rendered accessible for the purpose of changing the spool.

In the pulling out of the slide the looper moves approximately along the said line of feed, whilst in its operative position it is 45 situated on the inner side of a plane passing through the axis of the pin *b* (that is, the rocking axis of the looper carrier) at right angles to the line of feed, whereas after its 50 rocking movement, it is situated at an equal distance on the outer side of the said plane. Thus, in rocking, the loopers move instantly a considerable distance away from the plane passing through the axis of the path of the piercer at right angles to the feed line (that 55 is to say, in the present case, through the axis of the shaft *w*). Consequently there is plenty of room right and left for the location of a suitable feed device in the space situated between the two looper casings (and 60 immediately and laterally of the said space).

On the looper shaft bearing *k* of the looper carrier *a* there is mounted above the arm *l* a stop collar *y* for preventing any possibility of the arm coming in contact 65 with the fast revolving looper casing *i*.

Fig. 5 illustrates an improved device which is designed to prevent the spool holder *j* located in the looper casing *i* from revolving with the fast-revolving looper casing (which makes 3000 to 4000 revolutions a 70 minute) and is also designed to secure the spool holder in its position relatively to the looper carrier even whilst the said looper carrier is being rocked out of its operative position. The said device has the shape of 75 a substantially rectangular frame and consists in a fork *x* fixed to the bearing *k*. The two prongs of this fork are at first upwards and parallel to each other some distance apart, so as to allow a small portion 80 of the looper casing to project between them, after which the said prongs are bent at right angles to themselves so as to extend over the said small portion of the looper casing, and are thus continued in a common 85 horizontal direction towards each other. The free ends of the prongs bear from opposite sides against a nose *y* projecting from the spool holder, and they serve thereby as a stop or abutment for the said nose and 90 consequently also for the spool holder if and when the latter has a tendency to revolve with the looper casing. Moreover, this fork allows of the removal of the spool holder from the looper casing without requiring 95 any attaching devices whatever to be undone for this purpose. It is also to be understood that the fork may be constructed to allow of its being adjusted in the angular as well as in the vertical direction. In this 100 case a ring *x*¹ (Fig. 6) will be adjustably mounted on a downward extended part of the bearing *k* and the fork *x* fixed on this ring *x*¹ in a suitable recess formed thereon for guidance.

The constructional example as described and illustrated comprises two loopers. It is however obvious that the improvements of the invention may be applied also to hem-stitch sewing machines having only one 110 looper.

What I claim is:

1. A hem-stitch sewing machine comprising a rocking arm, a looper mounted rotatably in said rocking arm, a wheel fixed on 115 the looper axle, a wheel loosely mounted on the pivotal axle of the rocking arm for driving the wheel fixed on the looper axle, this fixed wheel rolling over said loose wheel in the rocking movement of said rocking arm; the pivotal axle of said rocking arm being adjustable horizontally in such a manner as to enable the distance of the looper from the line of the cloth feed to be varied.

2. A hem-stitch sewing machine comprising a carrier rotatable around a vertical pin fixed in the machine top plate, a lateral arm on this carrier in which arm the looper is carried in a rotatable manner; a first spur wheel loose on said pin, meshing with a sec- 125 ond spur wheel on the carrier, the carrier being 130

ond spur wheel fixed on the looper axle; a first helical wheel rigidly connected with said first spur wheel; and a (second) helical wheel which meshes with said first helical 5 wheel, and is mounted on a shaft extending at right angles to the path of the piercer, parallelly to the main driving shaft of the machine.

3. A hem-stitch sewing machine comprising 10 a rocking arm, a looper rotatable on the rocking arm, and located in front of, or behind the path of the piercer; a slide slideable in the table top of the machine and flush with the upper surface thereof, said slide being 15 located symmetrically to the centre line of the cloth feed, and movable along the line of the cloth feed; and a movable joint connection between said slide and said rocking arm, allowing the distance between looper 20 and slide to be varied; the relative positions of the pivotal axis of said rocking arm, the axis of said looper, said slide, and the path of said piercer being such that by pulling out said slide, said looper is moved approximately along the centre line of the cloth feed, and comes under the newly exposed portion 25 of the recess provided for the reception of said slide in the machine table top, and a vertical plane passing through the pivotal 30 axis of the looper carrier parallelly to the main driving shaft of the machine, passes approximately midway between the working position and the swung-out position of said looper.

35 4. A hem-stitch sewing machine comprising two loopers, rocking arms rotatably supporting said loopers, said arms having their

rocking axles located on opposite sides of the centre line of the cloth feed and of a vertical plane passing through the path of the piercer parallelly to the main driving 40 shaft of the machine, with a shaft, located in said plane, for operating said loopers, helical wheels, one for each of said loopers, mounted on said operating shaft, meshing with helical wheels fixed to spurwheels 45 which latter are loose on said rocking axles and which serve for actuating the looper-operating axles.

5. A hem-stitch sewing machine comprising 50 a swingable looper, an upwardly directed fork mounted on the looper carrier, having two prongs extending at right angles, and spaced apart to allow the outer portion of the looper casing to enter between the lower portions of said prongs, whilst the 55 free ends of the latter bear from opposite sides against a laterally projecting nose located on the spool holder mounted in said looper casing, so as to serve as stops or abutments for said nose and consequently for 60 said spool holder, and thereby prevent said spool holder from being moved by said looper casing, the arrangement being such that the part carrying said nose can be removed at any time without any fastening device having to be undone for this purpose.

In testimony whereof I have affixed my signature in presence of two witnesses.

EUGENE GEGAUF.
